United States Patent Office

Des. 229,443

Patented Nov. 27, 1973

229,443

TELEVISION RECEIVER CABINET

Melvin H. Boldt, Glenview, and David P. Chuboff, North Barrington, Ill., assignors to Zenith Radio Corporation, Chicago, Ill.

Filed Dec. 1, 1971, Ser. No. 203,930

Term of patent 7 years

Int. Cl. D14—03

U.S. Cl. D56—4 D

FIG. 1

FIG. 4

FIG. 2

FIG. 3

FIG. 1 is a perspective view of our design for a television receiver cabinet showing the front, top and left side thereof;

FIG. 2 is a front elevational view thereof;

FIG. 3 is a right side elevational view thereof; and

FIG. 4 is a cross sectional view thereof taken along lines 4-4 in FIG. 1.

The bottom and left and right sides are substantially plain and unornamental.

We claim:

The ornamental design for a television receiver cabinet, substantially as shown and described.
